DUAL FLOW CONTROL MECHANISM FOR
FLUSH TANK VALVES

Ralph H. Stegeman, Brea, Calif.

Application August 27, 1949, Serial No. 112,710

8 Claims. (Cl. 4—67)

1

This invention has relation to improvements in flush valves for toilet tanks such as used in the average home and has particular reference to means for controlling the volume of water to be discharged at each flushing operation. To this end the invention resides in the combinations hereinafter described in detail and preferred forms of the invention are illustrated in the accompanying drawings, of which:

Fig. 1 is a front sectional elevational view of a flush tank embodying the invention and with the front portion of the tank broken away in order better to illustrate the mechanism within the tank;

Fig. 2 is a fragmentary plan view of a portion of the mechanism of Fig. 1;

Figs. 3 and 4 are fragmentary front views of parts of the mechanism of Fig. 2, with parts thereof in different positions of adjustment;

Fig. 5 is a sectional plan view of the device taken substantially on line 5—5 of Fig. 1;

Fig. 6 is a front sectional elevational view of a somewhat modified form of the invention with the front wall of the tank broken away;

Fig. 7 is a fragmentary plan view of a portion of Fig. 6;

Figs. 8 and 9 illustrate a further modification of the invention; and

Fig. 10 is a fragmentary detail view of a portion of the device of Fig. 8 as viewed from the right side thereof.

Referring in the first instance to Fig. 1, it is noticed that the numeral 1 designates a flush tank of conventional shape and proportions into the bottom of which are fitted the usual inlet pipe 2 and discharge pipe connection 3. The inlet pipe 2 is shown broken away a short distance above the bottom of the tank but it is to be understood that this pipe rises through the tank and is, at the top thereof, fitted with any commercially well known type of flush valve the operation of which is controlled by a conventional float 4. Since such float controlled valve is universally used in flush tanks of this type and in order not to render the drawing too difficult to read, the valve is merely outlined at 6 in Fig. 5, it being thought sufficient to show that the stem 5 of the float 4 extends to such commonly used valve to control the operation thereof.

The outlet connection 3 is, at the top thereof, fitted with a seat 10 on which a valve 11 is shown seated, this valve being of the ordinary well known buoyant type. A lug 12 extends laterally from the discharge connection 3 to support thereon an overflow pipe 13 communicating through a

2

passage 14 within the lug with the discharge opening of the tank. Secured to the overflow pipe 13, a distance above the lug 12, is a laterally extending bracket 14, the outer end of which is bifurcated, see Fig. 5, to form at the ends thereof, a bearing for a rod 15. To the end of this rod is secured a head 16 which is shaped to receive therein and tightly to grip the outer end of an auxiliary float lever 17. A float 18 is secured to the opposite end of this lever.

Through the front wall of the tank extends a stem 20, see Fig. 2, to the outer end of which is secured the type of operating handle 21 ordinarily employed in flush tanks of the type herein considered. It is understood that this handle, being outside the front wall of the tank, would not appear in Figs. 1, 3 and 4, and it is shown in light, broken outline in these views merely to facilitate this description. The stem is shown seated for rotation within a bearing forming part of a connection 22 by means of which such stem is ordinarily supported on the tank. A bracket 23 is mounted on this connection and it is held by means of a nut 24, engaging screw threads of the connection, clamped rigidly in position thereon. In the outer end of this bracket is placed a stud 25, on which the inner end 26 of an arm 27 is rotatably mounted. The outer end of this arm, which for convenience of description is referred to as the trip lever, is perforated to receive the hook-shaped upper end of a link 28, the lower end of which is shaped to form a loop 29 horizontally extending from the link and of a size freely to encompass the stem 30 of the float valve 11. This stem is seated for vertical sliding movement within the bifurcated head 31 of an arm 32, the inner end of which is shaped to form a band 33 encompassing the overflow pipe 13 and clamped in position thereon by means of a screw 34. This connection from the float valve 11 to the trip lever 27 does not differ in principle from the float valve connections of the average flush tanks and functions in like manner.

A member 36 is, by a set screw 37, shown rigidly secured in position on the stem 20 directly below the trip arm 27 and the upper flat surface 36a of this member normally rides against the underside of the trip lever to maintain the connections to the flush valve in the position indicated in Fig. 1. It is for convenience of description hereinafter referred to as the trip lever cam. A second member 40 is rotatably hung on the stem 20 adjacent the cam and this member serves as a support for a rod 41 which extends downward from the member 40 and is intermediate its ends offset, as in-

dicated at 42, to form a shelf on which the outer end 17a of the float lever comes to rest when it reaches its uppermost position, as indicated in Fig. 1. When it is desired completely to flush the tank, it is required to swing the operating lever 21 counter-clockwise into the position indicated in Fig. 3, thereby to withdraw the float 11 from its seat and so to open the passage 3 for discharge of water from the tank in the well known conventional manner. It is important to note that during this operation the above mentioned auxiliary float mechanism remains in the position indicated in Fig. 1.

Further referring to the drawings, it is noticed that a stud 43 projects sidewise from the member 40 on to the top surface 36a of the member 36 against which this member comes to a stop when the operating lever is swung to flush the tank, as above described. It is furthermore important to note that the pressure of the member against this stud is effective to force the rod 41 against the end 17a of the float lever 17, thereby to insure continued engagement of the lever with the offset portion 42 during such flushing operation. When, on the other hand, the operating lever is swung in clockwise direction, as indicated in Fig. 4, it is noticed that the upper surface of the member 36 contacts this stud, thereby to cause the member 40 to swing on the stem 20 and so to withdraw the offset portion 42 of the rod from the end of the float lever. Also that, during this movement, the trip lever 27 is again swung upward to withdraw the valve 11 from its seat. The outrushing water releases both of the floats for downward movement and this movement continues until a projection 45 of the auxiliary float lever reaches and depresses the float 11 sufficiently to cause suction of the outrushing water to seat the float and so to disrupt the discharge long before the water level reaches the low level of conventional complete flushing. As indicated in Fig. 1, this intermediate water level will be located about half way between normal upper and lower levels when the auxiliary float mechanism is proportioned, as indicated in the drawing.

It is above mentioned that the float 4 controls the inlet valve to the tank in the conventional manner and the functioning thereof is in no way affected by this novel control mechanism. It is, however, well to limit the downward movement of this float in order to eliminate the possibility of the descending float colliding with any part of the control mechanism. I have, for this purpose, shown a bracket 38 mounted on the overflow pipe above the bracket 33. This bracket is, as best shown in Fig. 5, fitted with a laterally projecting stud 39 taking a position directly below the stem 5 of this float to form a stop checking downward movement of the float before any part of the control mechanism is reached.

It is time now to point out that it is possible to obtain similar results by means of a much simpler mechanism such as indicated in Figs. 6 and 7 of the drawings. In this case the tank, the outlet from the tank and the valve 11 may remain unchanged, except for the fact that the outlet connection is moved a short distance to the left and that it is given a half rotation in order to carry the overflow pipe 13 to the opposite side of the valve. The operating handle 21 and its stem 20 may also remain as above described, but in this case it is found necessary somewhat to modify the parts mounted on this stem to operate the trip lever 50. To this end

a member 51 is rigidly secured in position on the stem 20, as by means of a clamping screw 52 to form a cam, similar to the cam 36, the upper surface of which rests against the underside of the trip lever 50. A second member 53 is hung to rotate on the stem and it is fitted with a downwardly directed tubular extension 54, within which a rod 55 is held rigidly secured as by means of a clamping screw 56. This rod is near the lower end thereof, at 57, shown offset to form a stop for the upward movement of a float lever 58. This lever is pivotally hung on the end of a bracket 59 which, in turn, is rigidly clamped in position on the overflow pipe 13. A second bracket 60 is clamped in position on this pipe a distance above the bracket 59 and the outer end of this bracket is vertically perforated to form a guide for the valve stem 61. A link 62 extends from the top of this stem to the end of the trip lever 50. From the opposite end of the float lever 58 rises a stem 63 to support on the top thereof an auxiliary float 64. But, except for the fact that the rod 55 is offset to check upward movement of the lever, the operating lever connections may, if preferred, remain substantially as illustrated in Fig. 1.

When it is desired completely to flush the tank, it is merely required to rotate the stem 20 of the operating handle in counter-clockwise direction and the flushing will be accomplished in the conventional manner except that the float 64 will remain in its elevated position. When, on the other hand, the stem 20 is rotated in clockwise direction, it is found that the upper surface of the cam member 51 will contact and move a stud 65 of the member 53, thereby to swing the offset portion 57 of the rod 55 away from the end of the float lever and so permit the latter to swing downward as water discharges from the tank until the projection 66 of this lever strikes the float 11 and moves the latter downward until it reaches a position where the suction of the out rushing water causes the float to engage its seat and so to disrupt the discharge movement thereof. This lower position of the float and float lever is indicated in dotted outline of Fig. 6 and it is important to note that because the fulcrum of the auxiliary float lever is placed at a point nearer the bottom of the overflow pipe, the lever will engage and move the valve at the time the water level reaches a position about one-half of the distance between normal upper and lower levels.

While this simplified construction will function perfectly and can be relied upon to continue functioning until some parts thereof become so badly worn as to require replacements, it is found to have one serious objection. In examining Fig. 7, it is noticed that the pivotal point 67 of the auxiliary float lever is very close to the inner end thereof and comparatively far removed from its outer end, in which the float 64 is supported. The result is that the greater movement of the outer end of the float lever is translated into a much shorter movement of the inner end thereof, making it necessary manually to maintain the operating handle in its position after it has swung the rod 55 away from the float lever until the inner end thereof has moved upwardly far enough to make sure that, when the operating handle is released to allow the rod to return to its initial position, the inner end of the float lever will not again slip under the offset portion of the rod, as otherwise complete flushing of the

tank would result and the mechanism would become inoperative until manually reset.

It is because it is necessary to remember to delay release of the operating handle for a moment that I have adopted the preferred form shown in Fig. 1, in which the leverage of the auxiliary float lever 17 is such that the movement of the float 18 causes the inner end of the float lever to move below the offset portion 42 of the trip rod so quickly that it is not necessary to delay release of the operating handle 21 for return of the parts.

The arrangement of Figs. 8 to 10 is added merely to suggest a different manner of constructing the auxiliary float elevating mechanism. The mounting and positioning of the overflow pipe 13 may remain as in Fig. 7, but the connection from the operating handle 21 to the trip lever 70 is, in this case, substantially a duplicate of the arrangement shown in Fig. 1. Brackets 71, 72, are clamped in position on the overflow pipe 13 rigidly to support a rod 73 in parallel spaced relation to the pipe. A frame 75 is hung for vertical sliding movement on this rod. It is necessary to retain the bracket unturned on the rod, which latter for this purpose is shown square in cross-section. A bracket 76 projects sidewise from the frame to support an auxiliary float 17 by means of which the frame is normally maintained in the elevated position indicated in full outline in Fig. 8.

An arm 78 extends horizontally from the left side edge of the frame 75 and the end of this arm comes to rest on a shelf 79 of a rod 80 which, in turn, is secured in position within the rotary member 81 of the operating handle stem 20. As in the device of Fig. 1, it is found that a rotation of this stem in counter-clockwise direction will result in complete flushing of the tank without disturbing the position of the auxiliary flushing mechanism and that also in this case the cam member 82 contacts the stud 83 to maintain the rod 80 pressed against the end of the arm 78. But when the operating handle is moved clockwise the cam member moves against the stud 83 in the opposite direction to swing the rod 80 away from the end of the arm 78. The frame is now free to descend with the out rushing water to cause a pair of lugs 85, 86 of the frame to depress the float 87 until the latter, by suction of the discharging water is forced on to its seat.

The mechanism has the advantage over the device of Fig. 7, that the frame 75 moves with the speed of the receding water level and that, for this reason, it is not necessary to delay release of the operating handle for quite as long a period of time. But because a delay in the release of the handle still is required, it does not possess the great advantage of the preferred construction shown in Fig. 1.

It is seen from the foregoing description that I have provided tank flushing devices by means of which the amount of water to be discharged may be controlled by a simple movement of the operating handle. It is further to be noted that the amount of partial discharge may be varied by merely modifying the vertical position of the auxiliary flush lever 17 or 58 or the frame 75 relative to the auxiliary float. Other modifications may be embodied within the scope of the claims hereto appended.

I claim:

1. A flow control mechanism for a flush tank having a float actuated inlet valve, a flush valve, a pivotally hung trip lever, connections from said

lever to the flush valve and a pivotally hung operating handle movable in either direction to swing the trip lever to raise the flush valve to flush the tank, said mechanism comprising; a flow control member mounted for vertical movement within the tank, a float urging upward movement of the member, and an element engaging the member normally to maintain the member in elevated position, operation of the handle in one direction to raise the flush valve being effective to move the element thereby to release the member for downward movement with the outflowing water, the member depressing the flush valve as the water level descends thereby to cause suction of the outrushing water to draw the valve into closed position before complete flushing of the tank is attained.

2. A flow control mechanism for a flush tank having a float actuated inlet valve, a flush valve, a pivotally hung trip lever, connections from said lever to the flush valve and an operating handle having a stem rotatably fixed in the tank, the handle being movable in either direction to swing the trip lever to raise the flush valve to flush the tank, said mechanism comprising; a flow control member mounted for vertical movement within the tank, a float urging upward movement of the member, and an element hung for rotation on said stem, said element engaging the member normally to maintain the member in elevated position, operation of the handle in one direction to raise the flush valve being effective to move the element thereby to release the member for downward movement with the outflowing water, the member depressing the flush valve as the water level descends thereby to cause suction of the outrushing water to draw the valve into closed position before complete flushing of the tank is attained.

3. A flow control mechanism for a flush tank having a float actuated inlet valve, a flush valve, a pivotally hung trip lever, connections from said lever to the flush valve and an operating handle having a stem rotatably fixed in the tank, the handle being movable in either direction to swing the trip lever to raise the flush valve to flush the tank, said mechanism comprising; a flow control member mounted for vertical movement within the tank, a float urging upward movement of the member, an element hung for rotation on said stem, said element engaging the member normally to maintain the member in elevated position, a cam rigid on the stem, operation of the handle in one direction to raise the flush valve causing the cam to move the element thereby to release the member for downward movement with the outflowing water, the member depressing the flush valve as the water level descends thereby to cause suction of the outrushing water to draw the valve into closed position before complete flushing of the tank is attained.

4. A flow control mechanism for a flush tank having a float actuated inlet valve, a flush valve, a pivotally hung trip lever, connections from said lever to the flush valve and an operating handle having a stem rotatably fixed in the tank, the handle being movable in either direction to swing the trip lever to raise the flush valve to flush the tank, said mechanism comprising; a flow control member mounted for vertical movement within the tank, said member having a projection laterally extending therefrom, a float urging upward movement of the member, an element hung for rotation on said stem, said element engaging the member

normally to maintain the member in elevated position, a cam rigidly secured to the stem, operation of the handle in one direction to raise the flush valve being effective to turn the cam in the direction toward and to move the element thereby to release the member for downward movement with the outflowing water, the projection of the member depressing the flush valve as the water level descends thereby to cause suction of the outrushing water to draw the valve into closed position before complete flushing of the tank is attained.

5. A flow control mechanism for a flush tank having a float actuated inlet valve, a flush valve, a pivotally hung trip lever, connections from said lever to the flush valve and a pivotally hung operating handle movable in either direction to swing the trip lever to raise the flush valve to flush the tank, said mechanism comprising; a flow control lever mounted for vertical swinging movement within the tank, a float urging upward movement of the lever, and an element engaging the outer free end of the lever normally to maintain the member in elevated position, operation of the handle in one direction to raise the flush valve being effective to move the element thereby to release the lever for downward movement with the outflowing water, the member depressing the flush valve as the water level descends thereby to cause suction of the outrushing water to draw the valve into closed position before complete flushing of the tank is obtained.

6. A flow control mechanism for a flush tank having a float actuated inlet valve, a flush valve, a pivotally hung trip lever, connections from said lever to the flush valve and an operating handle having a stem rotatably fixed in the tank, the handle being movable in either direction to swing the trip lever to raise the flush valve to flush the tank, said mechanism comprising; a flow control lever pivotally mounted for vertical swinging movement within the tank, a float urging upward movement of the lever, an element hung for rotation on said stem, said element engaging the lever normally to maintain the lever in elevated position, a cam rigid on the stem, operation of the handle in one direction to raise the flush valve causing the cam to move the element thereby to release the lever for downward movement with the outflowing water, the lever depressing the flush valve as the water level descends thereby to cause suction of the outrushing water to draw the valve into closed position before complete flushing of the tank is attained.

7. A flow control mechanism for a flush tank having a float actuated inlet valve, a flush valve, a pivotally hung trip lever, connections from

said lever to the flush valve and an operating handle having a stem rotatably fixed in the tank, the handle being movable in either direction to swing the trip lever to raise the flush valve to flush the tank, said mechanism comprising; a flow control member mounted for vertical movement within the tank, a float urging upward movement of the member, an element hung for rotation on said stem, said element engaging the member normally to maintain the member in elevated position, a cam rigid on the stem, operation of the handle in one direction to raise the flush valve causing the cam to move the element thereby to release the member for downward movement with the outflowing water, the member depressing the flush valve as the water level descends thereby to cause suction of the outrushing water to draw the valve into closed position before complete flushing of the tank is attained, the element being shaped at the bottom thereof to limit downward movement of the member.

8. A flow control mechanism for a flush tank having a float actuated inlet valve, a flush valve, a pivotally hung trip lever, connections from said lever to the flush valve and an operating handle having a stem rotatably fixed in the tank, the handle being movable in either direction to swing the trip lever to raise the flush valve to flush the tank, said mechanism comprising; a flow control lever pivotally mounted for vertical swinging movement within the tank, a float urging upward movement of the lever, an element hung for rotation on said stem, said element engaging the lever normally to maintain the lever in elevated position, a cam rigid on the stem, operation of the handle in one direction to raise the flush valve causing the cam to move the element thereby to release the lever for downward movement with the outflowing water, the lever depressing the flush valve as the water level descends thereby to cause suction of the outrushing water to draw the valve into closed position before complete flushing of the tank is attained.
